UNITED STATES PATENT OFFICE.

GEORGE J. FLANAGAN, OF CHICAGO, ILLINOIS.

BOOK-HOLDER.

1,021,183.

Specification of Letters Patent. Patented Mar. 26, 1912.

Application filed August 31, 1910. Serial No. 579,950.

To all whom it may concern:

Be it known that I, GEORGE J. FLANAGAN, a citizen of the United States, residing at the city of Chicago, in the county of Cook 5 and State of Illinois, have invented a new and useful Improvement in Book-Holders, of which the following is a specification.

My invention relates to that class of devices for holding reference books, which is 10 adapted to close with and upon them when not in use, but which opens with them and at such time acts as a convenient support and holder while the books are being consulted.

15 The handling of heavy reference books, such as dictionaries, is always laborious and attended with damage to the covers and bindings. And many devices commonly called "dictionary holders" have been made 20 which, while of utility and convenience, have failed in some respect of providing freedom from injury to the volumes carried when in continued use. This has been due to the weight of the books being unequally distributed, causing tearing or twisting action 25 in the body thereof, and to friction between the supporting parts of the device and the outside of the bindings.

In my improved book holder, I provide 30 a plurality of supports for the book covers and so control their relation to each other at all periods of their movement and when at rest that a book may rest upon them without friction and practically as a part 35 thereof. The moving parts are adjustable to the size of the book to be carried and according to the relative range of movement desired. And the angle of the head itself 40 may be adjusted in its relation to the supporting standard.

The principles of my invention are illustrated in the drawings, in which—

Figure 1 shows a front elevation of my improved book holder horizontally placed 45 and partially open. Fig. 2 is a side elevation of the device as shown in Fig. 1. Fig. 3 is similar to Fig. 1, except that it shows the device adjusted for a larger book and fully open. Fig. 4 is an enlarged detail of 50 a take-up device for the adjusting strips. Figs. 5 and 6 show details of a device for adjustably limiting the movement of the book supports, and Fig. 7 is a detail of a joint for adjusting the holder at any desired angle to the supporting standard or 55 upright.

Further describing my invention with reference to the drawings, 1 and 2 are cover supports respectively provided with the members 3 and 4 which in turn are pivoted 60 to the upper ends of the arms 5 and 6. At the points 7 and 8 the said arms are pivotally attached to the cross bar 9 and the latter is supported upon the upright or stand by a jointed device hereinafter to be described. A connecting link 11 has one end pivotally attached to the arm 5 above its connection with the cross bar 9, and the lower end of said connecting rod is attached to the arm 6 below its connection with the 70 cross bar 9. A similar connecting link 12 has its ends pivoted in like manner to the arms 6 and 5 respectively above and below their connection with the said cross arm 9. By this arrangement any movement of 75 either of said arms is directly and positively communicated to the other arm to cause a reciprocal movement thereof. The members 3 and 4 are provided with shoulders 13 adjacent to the points at which they are pivoted, and on the arms below them by the pivot screws 14 are attached the revolute clips 15. The pivot points of the latter are eccentrically placed so as to bring the edges *a*, *b*, etc., in successive adjustable relation to the shoulder 13. Studs 16 are adapted to pass through the faces of the arms 5 and 6 to engage with depressions 17 in said clips and are held in relation thereto 80 by the springs 18. Suspending straps 20 have one end attached by the clips 21 to the underside of the cover support 1 and pass thence through openings in the downturned edges 22, 23 of the supports 1 and 2 to the shaft 24 which is journaled on the brackets 25 on the underside of the cover support 2. The said shaft 24 is provided with a key 25' and has a ratchet wheel 26 whose teeth are engaged by a suitable projection 27 on the spring actuated dog 28. It will be seen 90 that by rotary movement of this shaft the suspending strips 21 may be adjusted to limit the amount of separation which may be given to the cover holders and that the said strips also act as a support or sling upon which a book will rest, when the supports are closed, to include it between them.

In Fig. 7 is represented a side view of an adjustable supporting joint. The cross bar 9 is shown in cross section and the outer or face plate 30 of the joint is removed to show the disk 31 on the upward projection of 100 105 110 115

which 31' the cross bar is supported. The said disks or plates are arranged in pairs on each side of the middle piece 34 and are centrally secured together by the pivot bolt 32. 5 The said central piece moves with the plates 31. It has the slot 35 over the bolt 32 which allows it to pass backward when pressed by the thumb-button 36 to force the dog 37 on the rear thereof from the ratchet notches 10 38 in the rear edge of the face plate 30. The whole head is kept normally in fixed position, with the dog in engagement with said notches, by the spring 39 pressing on the projection 49 on the rear of the push 15 button disk.

I claim:

1. In a book holder; the combination of a cross bar, book supporting arms pivoted midway of their length to the ends of the 20 cross bars, and a plurality of links having their ends pivotally attached to the said arms respectively above and below their point of attachment to the cross bars.

2. In a book holder; the combination of a cross bar, book supporting arms pivoted midway of their length to the ends of the cross bars, a plurality of links having their ends pivotally attached to the said arms respectively above and below their point of 30 attachment to the cross bars, book cover supports on the said arms, and flexible means for securing the book cover supports to each other.

3. In a book holder; the combination of a cross bar, book supporting arms pivoted midway of their length to the ends of the cross bars, a plurality of links having their ends pivotally attached to the said arms re- 35

spectively above and below their point of attachment to the cross bars, book cover supports on the said arms, and flexible means for adjustably securing the book cover supports to each other. 40

4. In a book holder the combination of cover supports, an equalizing device to connect said supports, flexible devices for adjustably limiting their outward movement, and an adjustable stop to limit the angular movement of said supports. 45

5. In a book holder; the combination of a plurality of cover supports having downwardly turned adjacent edges, flexible slings to connect the said cover supports, and means for adjusting the length of said slings. 50

6. In a book holder; the combination of a plurality of cover supports having downwardly turned adjacent edges provided with perforations, flexible slings passed through said perforations, and means for adjusting the length of said slings. 55

7. In a book holder; the combination of a plurality of cover supports, a take-up shaft journaled on one of said supports and provided with locking means, and flexible slings having one end secured to the other book support and having the other end secured to said take-up shaft. 60 65

In witness whereof, I have hereunto set my hand, this 29th day of August A. D. 70 1910, in the presence of two subscribing witnesses.

GEORGE J. FLANAGAN.
